UNITED STATES PATENT OFFICE.

WALTER W. IDLE, OF ST. PARIS, OHIO.

CURRYCOMB.

1,324,899.

Specification of Letters Patent. Patented Dec. 16, 1919.

Application filed April 19, 1919. Serial No. 291,318.

To all whom it may concern:

Be it known that I, WALTER W. IDLE, a citizen of the United States, residing at St. Paris, in the county of Champaign and State of Ohio, have invented certain new and useful Improvements in Currycombs, of which the following is a specification, reference being had to the accompanying drawings.

10 This invention relates to curry combs, and particularly to curry combs provided with means whereby the teeth may be cleaned or cleared of hair, dirt, or other matter which will ordinarily accumulate upon the teeth.

15 The general object of my invention is to provide a very simply constructed, cheaply made, and easily operated curry comb of this description, having coacting with the teeth a cleaning plate through which the 20 teeth pass, the cleaning plate being longitudinally shiftable with relation to the teeth, and to provide a spring normally urging the plate in one direction relative to the teeth, and a lever so connected to the 25 cleaning plate that the plate may be shifted in a direction opposite to that in which the spring exerts its pressure.

A further object is to provide a curry comb of the character described wherein the 30 spring may be shifted into two positions, in one of which it will urge the cleaning plate away from the points of the teeth to allow the teeth to project a maximum distance beyond the cleaning plate and which, when 35 it is disposed in another position, will urge the cleaning plate toward the points of the teeth.

Other objects will appear in the course of the following description.

40 My invention is illustrated in the accompanying drawings, wherein:—

Figure 1 is a top plan view of a curry comb constructed in accordance with my invention;

45 Fig. 2 is an end view of the curry comb, partly in section;

Fig. 3 is a vertical section on the line 3—3 of Fig. 1; and

50 Fig. 4 is a transverse section of the curry comb showing the spring 27 transposed as to position.

Referring to these drawings, it will be seen that my improved curry comb consists of a back plate 10 having attached thereto 55 a plurality of rows of teeth, these rows of teeth being formed by U-shaped blanks 11 riveted to the back plate, and the outwardly extending flanges of which are serrated to provide the teeth 12. These teeth are thus arranged in rows longitudinally of the back 60 plate.

Attached to the back plate is a handle shank 13 which is off-set and connected in any usual or desired manner to a handle 14. Disposed to coact with the teeth is a 65 cleaning plate 15 which is formed with rows of perforations 16 to receive the teeth 12. This cleaning plate is formed at its extremities with lugs 17 which are upwardly turned and engage in notches 18 formed in the ends 70 of the back plate.

The back plate carries upon it upwardly extending ears 19, and pivoted between these ears is the rearwardly extending operating lever 20 which is twisted in its length and 75 formed to provide a thumb piece at its free end toward its handle. The central portion of this lever is formed to provide a downwardly projecting lug 21. This lug has a diagonally extending perforation 22. 80 Above this perforation 22 the lever is formed with a diagonally extending perforation 23, these perforations 22 and 23 extending reversely to each other. The lug is formed with a notch 24 at its forward edge. 85

Extending diagonally across the back plate is a bowed rod 25, the extremities of which are formed to loosely engage in perforations in the diagonally opposite ears 17, and extending through the perforation 23 90 is the bowed rod 26 having hook-shaped ends engaging the diagonally opposite ears 17. Thus, these rods cross each other at the point where they pass through the operating lever. 95

Under ordinary circumstances, an upwardly bowed spring 27 is disposed with its middle bearing against the under face of the lever adjacent the notch 24 and with its ends bent to engage in notches 28 formed 100 in the back plate. It will be obvious that under these circumstances, the upwardly bowed spring urges the lever outward from the back plate and thus acts to draw the cleaning plate inward or away from the 105 points of the teeth 12 but that the thumb of the operator may be used to press the lever 20 downward and thus project the cleaning plate toward the ends of the teeth and scrape off any hair, dirt, or other matter which may 110 be adhering to the teeth to thus cause the cleansing of the teeth.

Where this curry comb is being used on horses having tender skin and it is desired that the teeth shall project normally but a very slight distance, the spring 27 may be 5 transposed from the position shown in Fig. 2 to the position shown in Fig. 4 wherein the bowed spring is disposed between the cleaning plate and the back plate and, therefore, urges the cleaning plate toward the 10 points of the teeth. By shifting the lever outward away from the back plate, this cleaning plate may be drawn inward if desired.

In this arrangement, the cleaning plate 15 will keep the teeth from scratching the skin, while at the same time it is sufficiently yieldable so that the curry comb will do its proper work.

While I have illustrated a construction 20 which I have found to be thoroughly effective and convenient, yet I do not wish to be limited to this, as it is obvious that many changes might be made in the details of the construction without departing from the 25 spirit of the invention as embodied in the appended claims.

I claim:—

1. A curry comb of the character described comprising a back plate, a handle attached 30 thereto, rows of teeth all projecting from the back plate, a flat cleaning plate having perforations to receive said rows of teeth and slidably thereon and having ears at its ends extending upward beyond the back 35 plate, the ends of the back plate being

notched to receive said ears, a lever pivoted at its forward end upon the forward end of the back plate and having its free end extending toward the handle, and crossed, upwardly bowed rods engaged at their ends 40 with said ears, the lever having perforations at its middle through which said rods pass at their intersection.

2. A curry comb of the character described comprising a back plate, a handle attached 45 thereto, rows of teeth projecting from the back plate, a cleaning plate having perforations to receive said teeth and slidably thereon and having ears at its ends, the ears being disposed at the corners of the cleaning plate, 50 a lever pivoted to the back plate and having its free end extended toward the handle, crossed, outwardly bowed rods having engagement at their ends with said ears, a lever having perforations through which 55 said rods loosely pass, a bowed spring disposed against the back plate having its ends disposed in notches in the extremities of the back plate, the middle portion of the bowed spring engaging with the lever to urge it 60 outward, said spring being shiftable from its position between the lever and the back plate to a position between the back plate and the cleaning plate.

In testimony whereof I hereunto affix my 65 signature in the presence of two witnesses.

WALTER W. IDLE.
